UNITED STATES PATENT OFFICE.

LOUIS P. LAWRENCE, OF PASSAIC, NEW JERSEY, ASSIGNOR TO THE LAWRENCE RAILWAY BRAKE COMPANY, OF NEW YORK, N. Y.

LOCOMOTIVE-BRAKE.

SPECIFICATION forming part of Letters Patent No. 371,602, dated October 18, 1887.

Application filed November 4, 1886. Serial No. 217,939. (No model.)

To all whom it may concern:

Be it known that I, LOUIS P. LAWRENCE, of Passaic, in the county of Passaic, State of New Jersey, have invented certain new and 5 useful Improvements in Locomotive-Brakes, of which the following is a specification.

Heretofore the cylinders of power-brakes used on locomotives have usually been arranged between the driving-wheels, and in 10 most cases the shoes were arranged to act on those parts of the rims of the driving-wheels facing each other, whereby said shoes, when applied, had the tendency to spread the wheels, thereby injuring the tires of the wheels and 15 the axle-bearings of the same, thus rendering said brake highly disadvantageous. In some cases the brake-shoes have been applied at each side of the driving-wheels, which brake-shoes were connected. This connection was 20 open to objection, for the reason that the locomotives sway and rock to a certain extent, whereby rigid brake-shoe connections soon got out of order and would not operate in a proper manner.

25 The object of my invention is to provide a brake in which the brake-shoes are at both sides of the wheels, said brake-shoes being provided with suitable connections with each other and with the motor or brake-operating device between the wheels.

30 The invention consists in the combination, with the locomotive-wheel, of a brake-shoe saddle fastened at each side, boxes adjacent to each saddle, and a bar connecting the boxes of each wheel.

35 The invention further consists in swiveled connections between the brake-shoes and boxes.

40 The invention further consists in swiveled connections between the end of the piston-rods, of the cylinder located between the wheels, and devices connecting the piston with the brake-shoes.

45 The invention further consists in the construction and combination of numerous parts and details, as will be fully described and set forth hereinafter, and finally pointed out in the claims.

50 In the accompanying drawings, Figure 1 is a side view of part of a locomotive provided with my improved locomotive-brake, parts of

the locomotive being omitted and parts being in section. Fig. 1^a is a cross-sectional elevation through the power-cylinder of the brake. Fig. 2 is an enlarged longitudinal 55 sectional view of the power-cylinder, the pistons in the same, the connecting devices, and the brake-shoes at both sides of the rim of the wheels. Fig. 3 is a plan view of the power-cylinder and sectional plan views of the couplings and parts of the wheels. Fig. 4 is a sectional view of the tubular screw.

Similar letters of reference indicate corresponding parts.

The cylinder A is constructed of the cylindrical center piece, A', and the two end pieces, A². Between the inner end flange of each section A² and an end flange of the section A' the outer edge of a rubber ring, B, is clamped, the inner edge of which is provided with an 65 annular bead, which is sprung into an annular groove in the rim of a piston, C, of which there are two, said pistons C being each mounted on the inner end of a tube, C', passed through an aperture in the closed end of a 70 head A², the ends of the tubes C' sliding on the ends of a tube, D, held longitudinally on a spider-frame or cross-piece, D', in the center of the cylinder, so that the said tube can serve as a guide for the pistons C and the tube C'. 75 A spiral spring, D², is contained in the guide-tube D and in the two tube-sections C' shown in Fig. 2. Into the outer end of each tube C' a plug, E, is screwed, on the outer end of which a fork, E', is swiveled by a pin, E², 80 85 passed longitudinally through the plug.

To each fork E' a link, F, is pivoted, the opposite end of which is pivoted to the lower part of a lever, G, the upper end of which is pivoted to one of the inner brake-shoe saddles, H, to which saddles the brake-shoes H', resting against the tires I of the driving-wheels I', are fastened. Each lever G is provided with a series of apertures, G', to permit the links F being connected to the levers G at 90 95 different elevations.

To the upper part of the saddle H is pivoted a link, J, the upper end of which is pivoted to the frame J' of the locomotive. A fork, K, is pivoted to the lever G near its upper end, said fork being formed on the end of a pin, K', which is passed into the bore of a 100

tubular screw, L, provided on its outer end with a nut, L', the screw-thread of the screw extending from the inner end of the sleeve to within a short distance from the nut, as shown 5 at L², Fig. 4.

- The tubular screw L is screwed into a screw-threaded aperture, M', of a box, M, which is provided on its inner side with an opening or recess, N, as shown in Fig. 3, in which a nut, 10 N', is located, which is screwed on the screw-threaded end O' of a connecting bar or rod, O, extending across the wheel I' on the inside of the same, the screw-threaded end of the bar O passing through the bar M, as shown. A nut, 15 P, is screwed on that end of the screw-threaded part of the bar O' projecting beyond the outer end of the box M. The opposite end of each connecting-rod O is passed through a box, M, in the manner described, at the outside of the 20 wheel, said box M also having the recess N'. A turn-buckle, Q, is held by the nut P on the end of each box M at the outside of the wheel, and the turn-buckles of the two opposite sides of the locomotive are connected by 25 the rods Q'. The boxes M at the outsides of the wheels are also provided with screw-threaded apertures M', into which the tubular screws L are screwed; but in this case the outer ends of the pins K' are pivoted direct to 30 the brake-shoe saddles R, whereas at the inner sides of the wheel they are pivoted to the levers G, which in turn are pivoted to the saddles. The upper ends of the saddles R are connected by links R' with part of the frame 35 of the locomotive, as shown at the right-hand side of Fig. 2.
- A tube, S, is screwed on the section A of the cylinder and provided with the exterior collar, S', surrounded by a ring, T, formed on 40 the lower end of a bracket, T', fastened to the frame J'. Nuts T² are screwed on the tube S above the collar S' and resting upon the ring T, and support the cylinder from said ring. A pipe, U, is coupled to the upper end of the 45 pipe S by means of a coupling, which leads to an air-ejector, W, for vacuum-brakes, which air-ejector is located in the cab, and the construction of which is fully described in Letters Patent No. 300,876, dated June 24, 1884.
- To fully illustrate the different positions of the shoe I have shown the brake of one wheel applied and the other loose, which position is 50 practically impossible.
- The operation is as follows: When the brakes 55 are not applied, the pistons C are at the outer ends of the cylinders, as shown at the right-hand side of Fig. 2. When the brakes are to be applied, a vacuum is created in the cylinder, whereby the pistons C are pressed toward 60 the middle of the cylinder, the lower ends of the links G turning in the direction of the arrow x', Fig. 2, whereby the brake-shoes H are pressed against the tires of the wheels at the inner sides of the wheels. The boxes M at the 65 inner sides of the wheels are moved in the direction toward the middle of the wheels, whereby the connecting-rods O are drawn in

the same direction, as are also the boxes M on the outside of the wheels, and thus the brake-shoes on the saddles R are pressed against the 70 rims of the wheels at the outside. When air is admitted into the cylinder, the pistons C are pressed from each other by the action of the spring D², and both are in the position shown in the right hand side of Fig. 2. As the forks 75 F are swiveled in the plugs E, they can turn on the same. The pins K' being loosely mounted in the tubular screws L, they can turn in the same. The saddles can easily be adjusted, according as the tires of the wheels 80 and the brake shoes wear off, by turning the nuts L' to screw the tubular screws L outward more or less to bring the brake-shoes in proper relative position to the tires.

So as to protect the threads of the tubular 85 screws L from being clogged with dirt, oil, &c., when the said screws L project a greater or less distance from the apertures in the box M, the outer part of said screws are made plain, as shown at L², Fig. 4. Likewise, when the 90 brake-shoes and tires wear off, the boxes M on the opposite sides of the wheels can be adjusted by turning the nuts N' in the cavities N of the boxes, and by turning up the nuts P on the ends of the screw-threaded part of the 95 rod O, I am thus enabled to adjust the brakes at all times according to the wear of the tires and shoes. At the same time the connections between the levers and tubular piston-rods C' are swiveled, as are also the connections of 100 the brake, so that the swinging, swaying, rocking, and jolting of the locomotive do not in any way injuriously affect the connections of the several parts. If such should be the case; the slack can be taken up very easily and rapidly.

In this application I disclaim the combination, with a cylinder and piston, of a flexible ring fastened to the rim of the piston and inside of the cylinder, as set forth and claimed 110 in my application, Serial No. 217,940, filed November 4, 1886.

Having thus described my invention, I claim as new and desire to secure by Letters Patent—

1. The combination, with the cylinder, of a 115 fixed guide held longitudinally in the same, a tubular piston-rod mounted to slide on each end of the fixed guide, a piston on each tubular piston-rod, and a spring in the guide and the tubular piston-rods, substantially as shown 120 and described.

2. The combination, with a cylinder, of a piston, a piston-rod, a fork swiveled on the end of the piston-rod, and a brake-shoe saddle connected with said fork, substantially as shown 125 and described.

3. The combination, with a cylinder, of a piston and piston-rod, a fork swiveled to the outer end of the piston-rod, a link pivoted to the fork, and a lever pivoted to said link, and 130 a brake-shoe saddle hung on the frame of the locomotive and pivoted to the said lever, substantially as shown and described.

4. The combination, with a locomotive,

wheel, of a brake-shoe saddle at each side of the wheel, a box connected with each saddle, and a bar connecting the two boxes at opposite sides of the wheels, substantially as shown and described.

5. The combination, with locomotive driving-wheels, of a brake-shoe saddle hung at each side of the same, a box connected with each saddle, a connecting-bar extending across the wheels and having its ends passed through the boxes, nuts screwed on the ends of the rods, which nuts rest on the outer ends of the boxes, substantially as shown and described.

6. The combination, with locomotive driving-wheels, of a brake-shoe saddle hung on the frame of the locomotive at each side of the wheel, a box adjacent to each saddle, pins swiveled in the boxes and connected with the shoes, and a bar connecting the two opposite boxes of each wheel, substantially as shown and described.

7. The combination, with a locomotive driving-wheel, of a brake shoe saddle hung at each side of the same, a box adjacent to each saddle, tubular screws in the boxes, pins mounted to turn in the tubular screws and connected with the saddles, and bars connecting the two boxes of each wheel, substantially as shown and described.

8. The combination, with a locomotive driving-wheel, of a brake-shoe saddle hung at each side of the same, a box adjacent to each saddle, a tubular screw in each box, each screw having a nut on its outer end, and pins mounted to turn in the tubular screws, which pins are connected with the saddles, substantially as shown and described.

9. The combination, with a locomotive driving-wheel, of a saddle hung at each side of the same, a box adjacent to each saddle, a tubular screw in each box, each screw having a nut on its outer end and having the part adjacent to the nut made smooth on the outer surface, and a pin mounted to turn in each tubular screw, which pins are connected to the saddle, substantially as shown and described.

10. The combination, with a locomotive driving-wheel, of a saddle hung at each side of the wheel, a box adjacent to each saddle, a connecting-bar extending across the wheel and having its end passed through the boxes, a nut

screwed on each end of the bar, said nuts resting against the outer sides of the box, and a nut on each end of the bar within recesses of the boxes, substantially as shown and described.

11. The combination, with the two driving-wheels of a locomotive, of a cylinder hung between them, two pistons in the cylinder, a piston-rod projecting from each piston through the adjacent end of the cylinder, a brake-shoe saddle hung at each side of the wheel, levers connected with the brake-shoes at the inner sides of the wheels, a box adjacent to each brake shoe saddle, a tubular screw in each box, a pin mounted to turn in each tubular screw, the pins in the boxes at the inner sides of the wheel being pivoted to the levers which are pivoted to the brake-shoe saddles and the piston-rods, and the pins in the boxes on the outer sides of the wheels being pivoted to the brake shoe saddles, and of a bar extending across each wheel, the ends of the bar being held in the boxes on the sides of the wheels, substantially as shown and described.

12. The combination, with the driving-wheels of a locomotive, of brake-shoe saddles hung at each side of each wheel, a piston between the wheels for operating the saddles, and of a box adjacent to each saddle, bars connecting the boxes of each driving-wheel, and cross-rods connecting the boxes at the outer sides of the boxes at the opposite sides of the locomotive, substantially as shown and described.

13. The combination, with the driving-wheels of a locomotive, of a brake-shoe saddle hung at each side of each wheel, a cylinder between the wheels, a box adjacent to each saddle, a bar extending across the wheel and connecting the boxes of each wheel, and transverse bars connecting the outer boxes of each wheel on the opposite sides of the locomotive, which transverse rods have turn-buckles, substantially as shown and described.

In testimony that I claim the foregoing as my invention I have signed my name in presence of two subscribing witnesses.

LOUIS P. LAWRENCE.
